UNITED STATES PATENT OFFICE.

GEORGE T. PARR, OF ST. PAUL, MINNESOTA.

POWDER-PAD HOLDER.

Application filed November 30, 1920. Serial No. 427,429.

To all whom it may concern:

Be it known that I, GEORGE T. PARR, a citizen of the United States, residing at St. Paul, in the county of Ramsey and State of Minnesota, have invented a new and useful Improvement in Powder-Pad Holders, of which the following is a specification.

This invention relates to certain new and useful improvements in powder pad holders, and is particularly adapted for the holding 10 of powder pads which are used in billiard and pool parlors.

The primary object of this invention is the provision of a holder adapted to be secured to the under side of a billiard or pool table in an accessible place for the players, and is so constructed that the powder pad may be easily and quickly renewed from time to time as is desired.

20 A further object of this invention is the provision of a holder constructed to provide a powder holding portion and an indicating card receiving portion, the indicating card constituting a locking means to hold the pad 25 against accidental displacement from the holder.

A still further object of the invention is the provision of a powder pad holder which is simple and inexpensive and can be manufactured at a comparatively small cost.

With these and other objects in view, the invention consists in certain novel features, combination and arrangement of parts, as will be hereinafter more fully described and 35 pointed out in the claims hereto appended.

In the drawing,

Figure 1 is a perspective view of the holder as made in accordance with this invention,

40 Figure 2 is a perspective view of the holder looking in the direction of the bottom,

Figure 3 is a fragmentary portion of a billiard table with a holder attached thereto and in position for use,

45 Figure 4 is a fragmentary view of a table showing my improved holder attached thereto and partly in section to illustrate the securing of the pad in the holder,

50 Figure 5 is a transverse sectional view of a modified form of the invention showing the same secured to a table,

Figure 6 is a bottom plan view of the modification illustrated in Fig. 5, and

Figure 7 is a transverse sectional view of the ordinary type of powder pads.

Referring to the drawings, the numeral 5 indicates the holder which is constructed of suitable metal or other material suitable for the purpose, and it comprises a rectangular body 6 having its opposite ends bent over and arranged in spaced relation to the body to form end guide flanges 7. The bottom edge of the body 6 is bent at right angles to provide a supporting flange 8 between the adjacent edges of the flanges 7. The flange 8 and guide 7 constitute a retaining means for a powder pad 9. The upper edge of the body 6 is bent at right angles thereto in a direction opposite to the bending of the flange 8, and it has its opposite ends bent inwardly upon themselves in spaced parallel relation to form card receiving pocket 10. The bending of the upper edge of the body 6 constitutes a wall 11 and the flanges 12 of this wall at each end thereof are severed from the flanges 7 as at 13 so as to permit the upper terminals of the flanges 7 to form the bottom of the pockets 10, as clearly shown in Fig. 1 of the drawings.

80 The body 6 is provided with suitable openings 14 to receive fastening means 15 such as screws or the like, whereby the holder may be secured to the under side of a pool or billiard table A.

85 The wall 11 and flanges 12 forming the card receiving pocket 10 are adapted to retain a card 16 having printed or otherwise depicted thereon the word "Powder", indicating the position and place of the powder to the persons using the table. This card is an oblong strip, and has its opposite upper edges cut out as at 17, which permits it to be raised from engagement with the inner faces of the flanges 7 so as to permit 90 the removing from and placing in the holder a powder pad.

95 The powder pad which has the usual backing 18 as shown in Fig. 7 is slipped into the flanges 7, and is limited in its inward movement by the flange 8. The area of the backing 18 being less than that of the body 6 of the holder permits the backing to move inwardly beyond the adjacent edges of the flanges 7, these edges constituting the bottom wall of the openings 10, receive the lower edge of the powder card 16, when the same is slipped behind the flanges 12, and 100 105

by virtue of this card resting on the flanges 7, the powder pad is prevented from outward movement during use, it being necessary to raise the card 16 to remove and replace the powder pad.

The upper open ends of the pockets 10 are closed by bending a portion of the wall 11 over the same as at 20, and by virtue of the cut out portion 17 of the card, it is permitted to have sufficient vertical movement to permit of the renewing of the powder pad when desired.

In the modifications shown in Figures 5 and 6, the holder comprises a rectangular body 21 having its opposite side edges bent over against one face thereof to provide retaining flanges 22 for the backing 18 of a powder pad. The bottom edge of the body 21 is bent at right angles to provide a stop flange 23 which in conjunction with the side flanges 22 retains the powder pad in position. The free edge of the body 21 is offset laterally as at 24, and then extended at right angles to the body to provide a card receiving wall 25. The off-set portion 25 of the body 21 cooperates with the spaced transversely extending tongues 26, which are struck from the body to retain the powder pad against outward sliding movement when in the holder.

The tongues 26 are struck from the body and are tapered to give the necessary resiliency and normally bear outwardly against the backing 18 so as to cause sufficient pressure thereon to prevent accidental displacement of the powder pad, and as a further safeguard the off-set portion 24 which engages the outer edge of the backing 18 is provided.

40 What I claim as new is:

1. A powder pad holder comprising a support, a powder pad adapted to be positioned within said support, a flange, holding means secured to said flange, a card adapted to be positioned within said holding means.

2. A powder pad holder comprising a support, a powder pad adapted to be positioned within said support, a flange, holding means secured to said flange, a card adapted to be positioned within said holding means, said card holding means permitting the card to extend downwardly beyond the edge of said powder pad to lock the same in place.

3. A powder pad card holder comprising a sheet material body portion having its opposite ends and one side edge bent angularly with relation to the body to form flanges providing a powder card pocket, its free side edge bent at right angles to the body and in opposite direction to the end and

other side edge the ends of said upper edge being bent outwardly with respect to said edge to form a pocket for an indicating card, said pocket having its bottom wall formed by the forward end of the opposite ends of said body, whereby an indicating card when placed in said pocket will retain a powder pad card placed in the flanges against movement therefrom.

4. A powder pad holder comprising a body member, a guide-way formed along the same, a powder pad movably positioned within said guide-way, a card holder and a card positioned within the same for locking said pad from movement within the guide-way.

5. A powder pad holder comprising a body member, a guide-way, a powder pad slidably within said guide-way, a second guide-way, a card movable in said second guide-way, said second guide-way being arranged to permit the end of said card to extend beyond the edge of said powder pad to lock the same in place.

6. A powder pad holder comprising a body member, an inwardly turned edge transversely extending tongues, which are formed on the same, a flange extending upwardly from said powder pad holder at right angles thereto, a card holding means formed thereon, a powder pad adapted to be slidably positioned on said inwardly turned edges, and a card adapted to be positioned within said card holder, and to have its end projecting below the edge of said pad to lock the same in place.

7. A powder pad holder comprising a flat plate-like portion, inwardly turned edges formed on said flange, and a card slidably on said inwardly turned edges, a flange issuing upwardly from said plate-like portion at right angles thereto, inwardly turned ends formed on said flange, and a card slidably between said flange and said inwardly turned ends for locking said pad in place within the holder.

8. A powder pad holder comprising a flat plate-like portion, inwardly turned edges formed thereon, a powder pad slidable on said inwardly turned edges, a flange issuing upwardly from said plate-like portion at right angles thereto, inwardly turned ends formed on said flange, and a card slidably between said flange and said inwardly turned ends for locking said pad in place.

9. A sheet material body portion having its ends for locking said pad in place within the holder, said inwardly turned edges extending beyond the said card for supporting the same with its lower edge extending beyond the edge of said pad to lock the same in place.

GEORGE T. PARR

CERTIFICATE OF CORRECTION.

Patent No. 1,553,470, granted September 15, 1925.

to GEORGE T. PARR,

It is hereby certified that the above mentioned patent was erroneously issued to the inventor George T. Parr, whereas said Patent should have been issued to Olafson-Parr Mfg. Co., of St. Paul, Minnesota, said Company being assignee by mesne assignments, of the entire interest in said invention, as shown by the records of assignments in this office; and that the said Letters Patent should be read with this correction therein that the same may conform to the record of the case in the Patent Office.

Signed and sealed this 8th day of February, A. D. 1927.

William A. Kinnan,
Seal. Acting Commissioner of Patents.
